UNITED STATES PATENT OFFICE

CHARLES H. LITTLE, OF CLEVELAND HEIGHTS, OHIO

DRAFTING MACHINE

Original application filed January 13, 1927, Serial No. 160,840. Divided and this application filed June 12, 1929. Serial No. 370,219.

This invention relates to drafting machines and particularly to drafting machines of the well-known universal type such as illustrated in numerous prior patents granted to me, among which might be mentioned No. 1,003,765 of September 19, 1911. This type of machine, as is well known, has a parallel motion mechanism in the form of a jointed arm composed of two parallelograms, the end of one being adapted to be attached to an anchor either fixed to the drawing board or movable thereon, and the free end of the other carrying a protractor plate with a revoluble part circularly or angularly adjustable and having provision for receiving rulers disposed at right angles to each other. However, certain features of my invention are not confined to a machine having parallel motion mechanism of the specific form mentioned above. This application is a division of my prior application Serial No. 160,840, filed January 13, 1927.

The principal object of the invention is to provide certain improvements which simplify and reduce the cost of construction, increase the utility of the machine, and render certain parts more compact and rigid, thus increasing the accuracy and durability of the machine.

The present invention relates to certain improvements in the anchor and the anchor end of the machine and particularly to the construction of the anchor and of the anchor plate forming a part of the parallel motion mechanism and in the manner of attaching the machine to the anchor and detaching it therefrom, as well as in the provision of means by which the machine in folded condition but still attached to the anchor may be supported by the anchor at the back and parallel to the top edge of the board.

The invention may be briefly summarized as consisting in certain novel details of construction and combinations and arrangements of parts which will be described in the specification and set forth in the appended claims.

In the accompanying sheets of drawings showing an embodiment of the invention

which operates very effectively, Fig. 1 is a plan view of the drafting machine applied to a drawing board; Fig. 2 is a view looking toward the top edge of the drawing board and showing the machine folded and supported by the anchor at the back and parallel to the top edge of the board; Fig. 3 is a side elevation of the anchor end of the machine looking in the direction of the arrow designated 3 in Fig. 1; Fig. 4 is a sectional view substantially along the line 4-4 of Fig. 1; Fig. 5 is an end view of the anchor and certain of its associated parts looking in the direction of the arrow designated 5 in Fig. 1; Fig. 6 is a bottom view of the anchor end of the machine; Fig. 7 is a transverse sectional view substantially along the line 7-7 of Fig. 3; Fig. 8 is a plan view showing a portion of the drawing board and showing the anchor and a portion of the machine proper before the outer section of the anchor is swung down to the position shown in Fig. 2; Fig. 9 is a view looking at the top edge of the board and showing the anchor in the position shown in Fig. 2; Fig. 10 is a detail sectional view substantially along the line 10-10 of Fig. 8; and Fig. 11 is a similar sectional view substantially along the line 11-11 of Fig. 9.

Referring now to the drawings, 10 represents the drawing board to which is applied the drafting machine which in principle is similar to those illustrated in my prior patents. This machine is attached to the board through the medium of an anchor designated generally by the reference character 11. This part, as well as others now briefly referred to, embodies detail improvements which will be taken up later. A mid-anchor is herein illustrated, this anchor being applied to the upper part of the board between the top corners thereof. The drafting machine proper is attached to the outer end of the anchor 11 through the medium of an anchor plate 12 which is of novel construction and is adapted to be quickly and detachably connected to the anchor. Pivot-ed to this anchor plate are the parallel rods 13 of the upper parallelogram, the opposite

ends of these rods as well as the corresponding ends of the parallel rods 14 of the second parallelogram being pivotally connected to a common connecting or joint member in 5 the form of an annulus or disk 15.

The lower or outer ends of the rods 14 are pivotally connected to the protractor plate 16 attached to a ruler supporting member or arm pivotally connected to the protractor plate to turn about the center thereof and provided with a handle 17 and two chuck arms 18 and 19 arranged at right angles to each other and having chucks to 10 slidingly receive the chuck plates of a pair 15 of rulers 20 and 21, these generally consisting of scales or straight edges.

In this case, as is customary with mid-anchor machines, the axis of connection between the anchor plate 12 and the anchor is 20 inclined with reference to the top edge of the board, and the point of attachment of the anchor plate to the anchor is removed some distance from the board which, under ordinary circumstances, would leave the 25 anchor at all times projecting a considerable distance beyond the board. This is undesirable for certain uses, as, for example, for college or school room use where the boards are stored when not in use and where 30 as small a compass as possible is desirable. Accordingly, the anchor is made in two sections 22 and 23, the former being in this instance attached to the top edge of the board and the latter being not only detachably connected to it but also having pivotal connection therewith along an axis parallel to the top edge of the board. It is, therefore, not only possible to detach the longer portion 23 of the anchor from the relatively 35 short portion 22, but by pivoting or swinging the outer section on the inner section, the drafting machine may, when desired, be swung back along with the outer portion 23 of the anchor close to and on an axis parallel to the board, as is often desirable but 40 impossible with the ordinary mid-anchor. When the machine is in this position, it is 45 preferably supported on the anchor through the medium of a special supporting clip to 50 be described below in connection with Fig. 2.

The inner or base portion 22 of the anchor has two flanged ends which are attached to the edge of the board and an intermediate outwardly projecting part forming two 55 shoulders, which are straddled by two ears 23a and to which the part 23 of the anchor is pivoted. One pivot is formed by a pin 24 fixed in and projecting inwardly from one of the ears 23a. The other pivot is formed 60 by a screw 25 projecting through the other ear, the inner ends of the pin 24 and of the screw 25 being preferably beveled and engaging in beveled openings in the shoulders of the base portion 22. The screw 25 may 65 be provided with a lock nut when desired

so that it will be possible not only to pivot one part on the other but also to quickly detach the two parts and to firmly connect them together and to insure the outer part being restored to the same place or position 70 it occupied before removal.

One of the ears 23a is provided with an extension 23b projecting over one of the flanged ends of the base portion 22 of the anchor so as to limit the upward swinging 75 movement of the outer part 23 relative to the base part, and a cross bar 23c on the outer anchor member 23 carries a set-screw 26 which is adapted to engage the middle portion of the base member 22 of the anchor to 80 form an abutment which holds the outer anchor member in its normal extended position and serves also as a clamp to hold them in rigid relation.

As explained above, with this mid-anchor formed in two pivoted sections it is possible to swing or fold the machine back parallel to and along the top edge of the board and it was previously pointed out that when the machine is swung back to this position it is 85 preferably supported on the anchor, the two arms of the parallelogram then being folded together. To enable the anchor to support the machine in this position, it need only be provided with a supporting hook on which 90 the protractor end of the machine may engage and be supported. I have illustrated this in Figs. 2, 8, 9, 10 and 11 showing certain views of the anchor and illustrating the machine folded back and supported in the 95 position stated. This hook, which has been omitted from Fig. 1 for the sake of clearness, is preferably in the form of a stamping 23d pivoted by a screw 23e or equivalent means to the bar 23c of the outer anchor member 100 23. When the machine is in use on the board, this hook is, of course, not required and normally it is folded in and lies close to the cross bar 23c so as not to interfere with the free movement of the upper parallelogram 105 rods 13, but this stamping can be swung outward to serve as a hook-like support (see Fig. 11) for the protractor end of the machine when the machine is swung back beyond and parallel to the upper edge of the 110 board, as illustrated in Fig. 2, this hook being so positioned when the machine is swung to the position stated that it may be engaged by one of the rods 14 of the outer parallelogram or other appropriate part.

Taking up next the construction of the anchor plate 12 and the parts associated with it, this anchor plate, as illustrated in Figs. 4 and 5, has at its ends downturned ears 12a and 12b, the ear 12a having an inwardly extending pivot 27, and ear 12b carrying a U-shaped spring actuated lever 28 with a pivot 29 (Fig. 5) disposed oppositely with respect to the pivot 27. The pivots 27 and 29 are 125 adapted to engage in journals or trunnions 130

in opposite ends of the upwardly projecting end portion 30 of the outer anchor member 23 so that the machine as a whole is pivotally connected to the anchor. As previously pointed out, the axis of the pivotal connection between the anchor and the anchor plate is at an angle with respect to the top edge of of the drawing board.

The lever 28 is preferably in the form of a stamping one end of which projects upwardly above the anchor plate so that it can be conveniently grasped and pressed inward by the draftsman's finger to separate the pivots 27 and 29 so that the machine can be readily attached to or detached from the anchor. The pivot 29 is preferably a lug or boss struck from one side of the inner part of the lever, and above this lug there are a pair of similar lugs 31 struck from the opposite side, these two lugs bearing against the inner side of ear 12b and constituting the fulcrum about which the lever may rock. A coil spring 32 acting on the lever holds the pivots in engagement with the journals or trunnions of the anchor, this spring surrounding a screw 33 extending beneath plate 12 through the ears 12a and 12b and freely through the upper part of the inner portion of lever 28. This screw not only supports the spring but strengthens and increases the rigidity of the plate.

To attach the machine to the anchor, it is only necessary for the operator to press in on the upper end of the lever 28 so as to separate the pivots 27 and 29 and after the latter are brought into alignment with the trunnions at the outer end of the anchor, to then release the lever 28, whereupon the anchor plate is attached to the anchor with a snap action. In this way the machine not only can be attached quickly to the anchor but, as it is unnecessary for the draftsman to manipulate a screw to attach the machine, there is no danger of the machine being attached to the anchor either too tightly or too loosely, as might be the case if the connection were made by tightening a screw, particularly when the machine is in the hands of an inexperienced or careless draftsman, and when the machine is applied, it comes back to the same place it previously occupied, making it unnecessary to realign the machine or drawing.

The end of lever 28 lies along the upper left-hand end of plate 22 of anchor plate 12 as the same is viewed in Fig. 1. The location of the upstanding end of the lever at this point not only makes it convenient for the operator to manipulate the lever with his thumb while his hand is holding the anchor plate in applying or removing the machine, but as it is located at the end of the plate remote from the board, it does not reduce the clearance of the free movement of the ruler 20. It might be here stated also

that by arranging the pivots of the anchor plate 12 on the inner sides of downturned ears of the anchor plate, the pivot points are below and substantially no closer to the board than the pivots for the rods 13, so that by this construction, including the location of the lever 28, substantially maximum clearance is obtained for a given length of mid-anchor.

The rods 13 of the upper parallelogram are pivotally connected to the under side of anchor plate 12 through the medium of ball-pivots 34, this same type of joint being provided for both ends of the two sets of parallel rods 13 and 14. The ball-pivots engage in openings in the anchor plate 12 and rods 13, and, at the anchor end of the machine, and, in fact, at each end of the two parallelograms, the rods and members to which the rods are pivoted are held against the ball-pivots by spring pressure. At the anchor end of the machine the rods are pressed up against the ball-pivots by a plate 35 lying parallel to and on the under side of plate 12 forwardly of the ears 12a and 12b, and this plate 35 is pressed yieldingly upward by a bowed piece of spring metal 36. To hold this spring 36 under tension and to adjust the tension, a screw 37 passes centrally through plates 12 and 35 and through the spring 36, and on the under side of spring 36 the screw has threaded engagement with a nut 38 preferably in the form of a stamping having an upturned foot 38a (Fig. 7) engaging plate 35 immediately behind spring 36 whereby the nut is held from turning. This one screw and the nut which engages it hold together all the parts forming the joints between the rods 13 and the anchor plate.

It is desirable, of course, that the two parallelograms of the machine be held up off the board so that the protractor and the associated parts may be moved freely over the board, and this is generally accomplished by causing the weight of the parallelograms to be transmitted to the anchor. This is done, in this instance, through the medium of an adjustable abutment 39 which, for the sake of simplicity of construction, is in the form of a bushing or nut screwed onto the lower end of screw 37 and arranged to engage the outer anchor member 23. The manner in which this bushing functions to hold the parallelograms off the board or to transmit the weight thereof to the outer portion of the anchor is clearly illustrated in Figs. 4, 5 and 7.

As the rods 13 and the disk 15 are held off the board in a plane substantially parallel thereto, there is a considerable overhanging weight transmitted through the outer ends of the rods 13 to the anchor plate, and it is therefore essential that the connections

between the rods 13 and the anchor plate have the necessary stiffness in a direction at right angles to the board to hold the rods extending from the plate in the desired 5 direction (in planes at right angles to the board). To enhance the stiffness of the joints, the upper edge of the plate 35 is provided with upwardly extending lugs or feet 35a which engage the under side of the anchor plate beyond the ends of the rods 13. This gives plate 35 more stability and 10 greatly increases the stiffness of the joints in a direction at right angles to the board. Thus it will be seen that while the rods 15 are supported by the upper anchor plate 12 they are directionally supported by the lower plate 35 which is held in place in such a way that it is free to adjust or accommodate itself to wear.

20 While the joints between the rods and the anchor plate have stiffness in a direction at right angles to the board, as explained above, the joints between the rods and the disk 15 and at the protractor are semi-flexible or relatively flexible in the direction 25 stated so as to allow the ruler arm to at all times rest solidly on the board and adjust itself to the irregularities thereof.

The adjacent ends of the two pairs of 30 parallel rods 13 and 14 are, as previously stated, pivotally connected to the disk 15. The pivotal connections at these points are formed as at the anchor end, and, in fact, also at the protractor end, by ball-pivots, 35 the rods 13 being pivotally connected to the upper side and the rods 14 to the lower side of the disk 15. The two pairs of rod ends are pressed in engagement with the ball-pivots and the latter are held in engagement 40 with the disk by two bowed springs 40 which are held under tension by centrally disposed screws 41 screwed into the disk or annulus. The protractor ends of the rods 14 are pivotally connected to the 45 protractor plate 16 or an extension thereof by ball-pivots with the parts held yielding- 50 ly pressed together and held under tension by a suitable spring plate, not shown, overlying the ends of the rods. As the specific 55 form of connection between the rods 14 and the protractor plate, as well as the mode of pivotally connecting together the two parallelograms at the disk 15, forms no part of the present invention, further illustration of the same other than that shown in Fig. 1 is deemed unnecessary.

While I have shown the preferred construction of the anchor and of the parts forming the anchor end of the machine, the 60 same being an embodiment which operates with high efficiency, I do not desire to be confined to the precise details shown but aim in my claims to cover all modifications which do not involve a departure from the 65 spirit and scope of the invention.

Having thus described my invention, I claim:

1. A drafting machine of the parallel motion type having an anchor plate with a pair of downturned ears having relatively spreadable pivot forming means for attachment to an anchor on the drawing board, the pivot forming means of one ear comprising a spring actuated member with an operative portion adjacent the plate and adapted to be shifted to spread the pivot forming means.

2. A drafting machine having a parallel motion mechanism including two parallel rods and an anchor plate to which the ends 80 of the rods are connected, a member for holding said rods and the plate in pivotal engagement, a screw extending through the plate and through said member, and an adjustable supporting abutment on an extension of said screw to hold the rods off the drawing board to which the machine is attached.

In testimony whereof, I hereunto affix my signature.

CHARLES H. LITTLE.
